UNITED STATES PATENT OFFICE.

ROBERT HILPRECHT, OF LANSING, MICHIGAN, ASSIGNOR TO AMERICAN SUCTION GAS PRODUCER COMPANY, OF LANSING, MICHIGAN, A CORPORATION OF MICHIGAN.

GAS-PRODUCER.

No. 824,359.

Specification of Letters Patent.

Patented June 26, 1906.

Application filed June 17, 1905. Serial No. 265,778.

To all whom it may concern:

Be it known that I, ROBERT HILPRECHT, a subject of the German Emperor, residing at Lansing, in the county of Ingham and State 5 of Michigan, have invented certain new and useful Improvements in Suction Gas- Producers, of which the following is a specification, reference being had therein to the accompanying drawing.

10 The invention relates to suction gas-producers, and has for its object the obtaining of a construction capable of being formed in relatively small units.

In the present state of the art suction gas- 15 producers are usually formed with a casing in which a mass of fuel is placed, the fuel being centrally fed into the casing and the suction for removing the gas being applied to the sides of the mass. With the present construction the fuel is fed into the chamber 20 from the sides, and the gas is drawn off at the center. Furthermore, a relatively large chamber is formed within the center of the mass of fuel in which the gas generated is 25 collected, and the extended surface of this chamber is utilized for absorbing the heat from the gas and transferring it to the surrounding mass of unburned fuel. A steam or vapor generator is also arranged within 30 this central chamber.

In the drawing the producer is illustrated in vertical central section.

A is an outer casing, the lower portion of which is provided with a fireproof lining B, 35 which is of a conical or a downwardly-tapering form. C is a grate at the lower end of this lining, this being preferably of a basket form and depending into an ash-pit chamber D.

40 E is a fuel-hopper at the upper end of the casing.

Within the casing A is arranged a second casing F, which at its upper end has a conical portion G projecting upward toward the base 45 of the fuel-hopper E. Thus the fuel dropping from the hopper E will be deflected laterally by the cone G to the annular space between the inner casing F and the outer casing A. The lower end of the casing F is some 50 distance above the grate, so as to permit the fuel passing downward through the annular

space between the casings to spread over the entire grate area.

At the upper end of the casing F is arranged a water-receptacle H, and the steam generated therein by the heat of the gases will pass upward in the conical casing G to a vapor-discharge conduit I. This conduit is preferably provided with a discharge-nozzle J, which is arranged as an injector within the conduit K, which conduit is connected with the upper end of the fuel-chamber between the casings F and A. Thus any distilled gases passing off from the fuel will be propelled by the jet from the nozzle J through the conduit K, which leads downward to the chamber D beneath the grate. This conduit K also connects with the air-inlet conduit L, which is mixed with the vapor and gas entering the ash-pit chamber.

With the construction described a relatively small mass of fuel is held within the casing A at any one time, and the device is operative for the production of a relatively small amount of gas, which has not proven 75 practicable with the constructions heretofore used. The suction-conduit M, which connects with the chamber within the casing F, is connected with the engine, and whenever suction is produced the required volume of 80 air, steam, and distilled gas is drawn into the ash-pit chamber D and thence through the grate and mass of incandescent fuel supported thereon into the central chamber.

It will be noted that the casing F forms, in 85 effect, a suction-hood arranged above the grate and that by reason of the tapering form of the lining B the fuel is fed between said hood and grate from the periphery thereof toward the center. Thus the layer of fuel 90 between the hood and grate is maintained of uniform thickness.

What I claim as my invention is—

1. A suction gas-producer comprising an outer casing, an inner casing open at its lower end and spaced from said outer casing to form an annular fuel-chamber therebetween, a grate beneath the opening of said inner casing, a vaporizer within said inner casing, a fuel-hopper above said vaporizer, and a suction-conduit connected with the gas-chamber within said inner casing.

2. In a suction gas-producer the combination with a grate, of a superposed suction-hood tapered toward both ends and a fuel-hopper upon the upper end of said hood, for the purpose described.
3. In a suction gas-producer, the combination with a grate, of a superposed suction-hood tapered at both ends, a casing surrounding said hood and tapering toward said grate, and a fuel-hopper upon the hood the space between said hood and casing forming a fuel-magazine from which the fuel is centrally fed between the hood and grate to maintain a layer of uniform thickness.
4. In a suction gas-producer, the combina-

tion with a grate, a superposed suction-hood, a casing surrounding said hood, a vaporizer in said hood, and a fuel-hopper upon said vaporizer, for the purpose described.

5. In a suction gas-producer, the combination with a grate, of a superposed suction-hood tapered at both ends, a casing surrounding said hood and tapering to said grate, and a vaporizer within said hood.

In testimony whereof I affix my signature ²⁵ in presence of two witnesses.

ROBERT HILPRECHT.
